(57) **CLAIM**

The ornamental design for a tire tread, shown and described.

DESCRIPTION

FIG. 1 is a perspective view of a tire tread, it being understood that the tread pattern repeats uniformly throughout the circumference of the tire.

FIG. 2 is a front elevation view thereof.

FIG. 3 is a right side elevation view thereof; and,

FIG. 4 is an enlarged fragmentary front view thereof.

The broken lines shown in the drawings are for the purpose of showing environmental structure only and form no part of the claimed design.
